ATTY'S.

UNITED STATES PATENT OFFICE.

BENJAMIN H. JONES, OF ST. LOUIS, MISSOURI.

CORNER-FASTENING FOR BEDS.

No. 809,447.

Specification of Letters Patent.

Patented Jan. 9, 1906.

Application filed April 14, 1905. Serial No. 265,545.

To all whom it may concern:

Be it known that I, BENJAMIN H. JONES, a citizen of the United States, residing at St. Louis, Missouri, have invented a certain new and useful Improvement in Corner-Fastenings for Beds, of which the following is a full, clear, and exact description, such as will enable others skilled in the art to which it app-

perts to make and use the same, reference 10 being had to the accompanying drawings, forming part of this specification, in which—

Figure 1 is a side elevational view of my improved corner-fastening for beds, showing the bedpost and connecting-rod in dotted lines. Fig. 2 is a top plan view of the same, 15 and Fig. 3 is a fragmentary perspective view of a bed with my invention applied.

This invention relates to a new and useful improvement in corner-fastenings for beds, 20 the object being to dispense with separate pins or fastening-collars on the bedposts and to use instead thereof the connecting-rods which are commonly employed to tie the bedposts together. With this object in view 25 the invention consists in the construction, arrangement, and combination of the several parts, all as will be hereinafter described and afterward pointed out in the claim.

In the drawings, 1 indicates a metal bed- 30 post, and 2 is the connecting-rod serving to tie the two bedposts at the head or the foot of the bed together.

35 3 is a casting to which the rail-angle 4 (or the tubular rail, as the case may be) is secured. Casting 3 is provided with hooks 5 for taking in the rod 2, these hooks, as shown in Fig. 2, being laterally displaced with respect to the casting. In line with the rail 4 there are two bearing-points 6, located below 40 and above the hooks 5, so that when the rail is secured in position the casting engages the post above and below the hook 5, making with the engagement of hook 5 with rod 2 a

three-pointed bearing. Casting 3 is strengthened by suitable webs and flanges, as shown, 45 and by having two hooks 5 it is obvious that the rail can be turned end for end to reverse the angle 4, if desired. Where a tube is used instead of the angle 4, only one hook is necessary, as there will be no occasion to reverse 50 the tube.

By referring to Fig. 3 it will be observed that by connecting the rails 4 by cross-pieces arranged at their ends a frame will result, which frame is desirable in certain classes of 55 beds or cots in lieu of the removable side rails. The construction of the frame, to the end rails of which are connected the woven-wire or canvas mattress, is so well understood that I deem it unnecessary to illustrate the same 60 in the drawings.

I am aware that changes in the construction, arrangement, and combination of the several parts of my device can be made and substituted for those herein shown and de- 65 scribed without in the least departing from the nature and principle of my invention.

Having thus described the invention, what is claimed as new, and desired to be secured by Letters Patent, is—

70 In a corner-fastening for beds, the combination with a metal bedpost and its connecting tie-rod, of a casting, a rail secured to said casting, a laterally-extending hook on said casting for engaging the tie-rod, and bearing-points on the casting located above and below the hook and in line with the post for engaging said post; substantially as de- 75 scribed.

In testimony whereof I hereunto affix my 80 signature in the presence of two witnesses, this 6th day of April, 1905.

BENJAMIN H. JONES.
